UNITED STATES PATENT OFFICE

138,474

DESIGN FOR A TELECOMMUNICATION SUBSTATION SET

Virginia A. Merrill, New York, N. Y., and Noah S. Terry, Freeport, N. Y., assignors to Bell Telephone Laboratories, Incorporated, New York, N. Y., a corporation of New York

Application May 12, 1944, Serial No. 113,564

Term of patent 14 years

(Cl. D26—14)

To all whom it may concern:

Be it known that we, Virginia A. Merrill and Noah S. Terry, citizens of the United States of America, residing at New York, in the county of New York and State of New York; and at Freeport, in the county of Nassau and State of New York, respectively, have invented a new, original, and ornamental Design for a Telecommunication Substation Set, of which the following is a specification, reference being had to the accompanying drawing, forming a part thereof.

Fig. 1 is a perspective view of the telecommunication substation set, showing our new design with the handset omitted for convenience of illustration;

Fig. 2 is a side elevational view of the set with the voice communication handset shown in dotted lines;

Fig. 3 is a top plan view of the set; and

Fig. 4 is a front elevational view thereof. The characteristic features of the present design are shown in full lines in the drawing.

We claim:

The ornamental design for a telecommunication substation set, as shown and described.

VIRGINIA A. MERRILL.
NOAH S. TERRY.
